Primary Examiner — Cynthia M. Chin(74) *Attorney, Agent, or Firm* — Law Offices of Steven W. Weinrieb(57) **CLAIM**

The ornamental design for a tent, as shown and described.

DESCRIPTION

FIG. 1 is a front, left side, top perspective view of a tent showing my new design;

FIG. 2 is a front, left side, top perspective view thereof showing the tent when the tent is staked to the ground and when the front and side flaps are closed;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the tent that form no part of the claimed design.
